SKILL DART GAME APPARATUS

Leon E. Moss, Collingswood, N. J.

Application June 9, 1938, Serial No. 212,837

6 Claims. (Cl. 273—102.2)

This invention relates to game apparatus and particularly requiring the skillful throwing of a dart for effective scoring.

It is further aimed to provide such a structure utilizing a rotary member carrying a plurality of plugs constituting targets for the darts, which plugs in a predetermined position, are adapted to automatically register a score.

It is further aimed to provide such an apparatus with a system wherein the score of different players will be electrically indicated.

Still further, it is aimed to provide a novel construction of plug both from the standpoint of its mounting and the closing of an electric circuit through scoring mechanism or registers.

The more specific objects and advantages will become apparent from a consideration of the description following taken in connection with the accompanying drawings illustrating an operative embodiment.

In said drawings:

Figure 1 is a view showing the apparatus in front elevation;

Figure 2 is a view of the apparatus in rear elevation;

Figure 3 is a side elevation of the apparatus;

Figure 4 is an enlarged section taken on the plane of line 4—4 of Figure 1;

Figure 5 is a detail section taken on the line 5—5 of Figure 4;

Figure 6 is a detail section taken on the line 6—6 of Figure 4;

Figure 7 is a detail section taken through parts adjacent one of the plugs and showing the switch in closed position;

Figure 8 is a perspective, collectively showing the different parts of one of the plugs and its attaching means;

Figure 9 is a horizontal section with the control switch of the scoring mechanism;

Figure 10 is a vertical section taken substantially on the plane of line 10—10 of Figure 9; and

Figure 11 is an electrical diagram.

Referring specifically to the drawings wherein like reference characters designate like or similar parts, 10 designates a panel or board which is usually disposed vertically. The rear of such panel is a bearing bar 11 connected to the panel by means of bolts 12 on which spaces 13 are threaded.

Said panel 10 has a central cut-out or opening 14 which is occupied by a rotatable disk 15, journaled on a thick spindle 16 in the form of a bolt which is fastened by nuts 17 and 18, rigidly to the bearing bar 11. Said disk 15 has a recess 19

receiving the head 20 of said spindle or bolt 16. The shank 21 of the latter passes through and is journaled in a spider or bracket 22 fastened at 23 to the disk.

Suitably fastened to the rear of said disk 15 is a pulley rim 24, the fastenings being shown at 25. An endless belt 26 traverses said pulley flange 24 and is driven for example by an electric motor 27 suitably mounted at 28 on the bearing bar 11. In a row concentric with the spindle 16, a series of equi-distantly spaced recesses or openings 29 are provided through the disk 15. Disposed for sliding in said openings 29 are target plugs 30 made for instance of cork, wood or any other desired material. Such target plungers are detailed in Figure 8. Each plunger has a diametric slot 31 in one end thereof whereby such end is bifurcated to straddle a bar 32 fastened diametrically across each opening 29 at the back thereof and to the disk 15 as at 33. An arched spring 34 is interposed between the base of the slots 31 and the bars 32 and retaining plates or disks 35 are fastened across the rear end of the target plungers 30 as at 36. Said springs 34 normally urge the target plungers to their outermost positions and permit them to slide inwardly to impact upon targets being struck by a dart.

The score of the thrown dart hitting the target plug 30 at the desired or predetermined location, for instance between the represented darts at 36, delineated on the panel 10, is adapted to be automatically registered or indicated through the illumination of lamps 37 in boxes 38 disposed for instance on opposite sides of the panel 10. The number of lamps 37 in each box corresponds to the number of the target plungers 30 so that there is a lamp in each box to illuminate successively the lamps corresponding to the struck target plungers.

The apparatus is used for the game played, preferably by two players and preferably for a predetermined length of time for instance three minutes, determined by a time clock 39 adapted to be set in operation through the deposit of the proper coin in the coin control mechanism 40. Such time clock 39 is in the electric circuit wiring 41, receiving its energy from any desired source and the wiring including a transformer at 42 and electromagnetically operated circuit closing devices 43, to operate the lamps 37 when darts strike the plunger targets. To this end, and arranged in said circuit are normally spaced contacts 44 mounted on the bar 11. One of the contacts 44 has a transverse arm or extension 45. When a target plug 30 is struck by a dart, 55

the impact moves it inwardly so that its disk 35, when opposite the arm 45 will move the latter inwardly and cause the contacts 44 to engage and thereby two conductors 46 close an electric circuit in the wiring 41, to illuminate one of the lamps 37.

Attention is called to the fact that while there are two boxes 38 and lamps 37, that the lamps of only one box at a time can be lighted and this depends upon operation of a switch 47 as detailed in Figures 9 and 10. The circuit or wiring 41 includes conductors 48, fingers 49 and fingers 50 which are normally disengaged therefrom. The fingers 49 are simultaneously operable against the contacts 48 through depression of a button 51 and the fingers 50 are simultaneously engageable with the contacts 48 through depression of a button 52. Thus if the button 51 is depressed, lamps 37 of only one box 38, corresponding thereto, will be lighted according to the accuracy of the player while if the button 52 is depressed, the lamps of the other box only will be illuminated, depending upon the accuracy of the player.

Various changes may be resorted to provided they fall within the spirit and scope of the invention.

I claim as my invention:

1. Apparatus of the class described having a disk, means mounting the disk for rotation, targets carried by the disk, mounting means for the disk, a motor on the mounting means, and a drive from the motor to the disk, said targets being movable relatively to the disk, and signal means including an electric circuit having a switch common to all of the targets arranged to be closed through sliding of a target registering therewith occasioned by impact of a dart with the latter target.

2. Apparatus of the class described having a disk, means mounting the disk for rotation, targets carried by the disk, mounting means for the disk, a motor on the mounting means, and a drive from the motor to the disk, said targets being movable relatively to the disk, and signal means including an electric circuit having a switch common to all of the targets arranged to be closed through sliding of a target registering therewith occasioned by impact of a dart with the latter target, said signal means comprising separate signals, and switch means in the circuit

operable to determine the signal to be operated.

3. Apparatus of the class described having a panel provided with an opening, a disk rotatable in the opening, a bar supported from the panel, means mounted on the bar journaling the disk for rotation, target plugs slidably mounted by the disk, and signal means having a control part mounted on the bar for operation through the sliding movement of the target plugs occasioned by impact of a dart therewith.

4. Apparatus of the class described having a panel provided with an opening, a disk rotatable in the opening, a bar supported from the panel, means mounted on the bar journaling the disk for rotation, target plugs slidably mounted by the disk, and signal means having a control part mounted on the bar for operation through the sliding movement of the target plugs occasioned by impact of a dart therewith, said part being a switch and electric circuit containing the signal.

5. Apparatus of the class described having a panel provided with an opening, a disk rotatable in the opening, a bar supported from the panel, means mounted on the bar journaling the disk for rotation, target plugs slidably mounted by the disk, signal means having a control part mounted on the bar for operation through the sliding movement of the target plugs occasioned by impact of a dart therewith, said target plugs being bifurcated, bars on the disk disposed in the bifurcations, plates secured to the target plugs and disposed over the bifurcations, and spring members between the bases of the bifurcations and said bars.

6. Apparatus of the class described comprising a mounting member, said member having an opening, a target plunger slidably disposed in said opening, said plunger at the rear end being bifurcated and projecting beyond the mounting member, a bar on the mounting member spanning the opening and disposed in the bifurcation, a plate secured to one end of the target plunger and disposed across the bifurcation, spring means in the bifurcation between the base thereof and the bar, and signal means for operation through the sliding movement of the target plunger occasioned by impact of a dart therewith.

LEON E. MOSS.
